MINIATURE AIRPLANE

Joseph E. Grant, Beverly Hills, Calif.

Application October 21, 1941, Serial No. 415,930

19 Claims. (Cl. 46—76)

This invention relates to miniature airplanes. The general object of the invention is to provide an improved miniature airplane wherein the supporting frame for the airplane is made of paper or other flexible material.

A more specific object of the invention is to provide an airplane including an airfoil wherein the body and spars are each made of paper folded to shape.

Another object of the invention is to provide a novel airfoil.

An additional object of my invention is to provide a novel airplane wing beam.

A further object of the invention is to provide a novel blank for use in making an airplane wing.

Another object of the invention is to provide a novel fuselage for an airplane.

Further objects and advantages of the invention will be apparent from the following specification taken in connection with the accompanying drawings wherein:

Fig. 1 is a fragmentary view of a blank showing my invention;

Fig. 2 is a fragmentary top view on an enlarged scale showing an airfoil embodying the features of the invention;

Fig. 3 is a fragmentary top plan view of a spar member used with my invention;

Fig. 4 is an end view of the spar member shown in Fig. 3;

Fig. 5 is a fragmentary section taken on line 5—5, Fig. 2;

Fig. 6 is a section taken on line 6—6, Fig. 2;

Fig. 7 is a top plan view of an airplane embodying the invention;

Fig. 8 is a side elevation of the airplane;

Fig. 9 is an extended view on an enlarged scale partly in elevation and partly in section showing the invention;

Fig. 10 is an enlarged elevation partly in section showing a rudder and stabilizer member;

Fig. 10A is a fragmentary section taken on line 10A—10A, Fig. 10;

Fig. 11 is a section taken on line 11—11, Fig. 10;

Fig. 12 is a section taken on line 12—12 of Fig. 9;

Fig. 13 is a sectional view showing a fuselage embodying a single member.

Fig. 14 is a plan view of a modified blank;

Fig. 15 is a top plan view with parts broken away showing an airplane made from the modified blank;

Fig. 16 is a section taken on line 16—16, Fig. 15;

Fig. 17 is a section taken on line 17—17, Fig. 15;

Fig. 18 is a plan view showing the brace member; and

Fig. 19 is a section taken on line 19—19, Fig. 15.

Referring to the drawings by reference characters, I have shown at 10 in Fig. 1 a blank embodying the features of my invention. This blank is preferably made of a single sheet of paper or similar material and includes a body portion 11 and rib forming portions 12 all of which are integral.

The body portion 11 as shown is provided with four slits arranged in two parallel sets as indicated at 13, 14, 15 and 16. The slits 13 and 15 constitute one pair and the slits 14 and 16 constitute a second pair. Ends of the slits are spaced apart as indicated at 16' and the slits extend through the rib portions 12 and to the ends of the blank.

The body portion 11 is provided with transverse score lines 17 and the rib forming members 12 are provided with longitudinally extending score lines 18. The rib portions 12 extend in front of and to the rear of the body portion 11 and they are each provided with integral tabs 19 which may be attached to a covering (to be later described) to form a wing 19'. The rib forming members are of such a size as to provide a correct contour in the finished wing.

At each end of the blank I provide a half-rib member 20 which, as shown in Fig. 5 serves as an end closure for the assembled wing. The half rib member 20 includes tabs 21.

In Fig. 3, I show a spar member indicated at 22. This spar member is preferably made of paper and is of general U shape and includes a base 23 and a pair of legs 24.

In the assembly of the wing 19' the blank shown in Fig. 1 is folded on the score lines 17 and 18 to provide a plurality of V-shaped grooves 25, as shown in Fig. 5. After this is done one of the spar members 22 is inserted in the slits 13 and 15, and the base 23 of this spar member is arranged substantially flush with the crest of the V's. A second spar member is then inserted in the slits 14 and 16 with the base of the second spar member substantially flush with the bottom of the crests of the V members.

In this way an interlocking assembly is provided which then receives a covering 26. This covering is connected to the tops and bottoms of the V's and is connected to the bases 23 of the two spar members and is also connected to

the tabs 19 and 21 so that the parts are firmly connected. The top covering may be slightly shorter than the bottom covering so that the two halves of the wing will incline slightly toward the center to form a dihedral angle. The front and rear edges of the wing may receive a binding strip 27 and a binding strip 28 may be placed in the ends of the wing.

The wing 18' is preferably mounted on a fuselage which is indicated generally at 39 and is best shown in Fig. 9. This fuselage consists of an upper member 31 and a lower member 32. These members are complementary one to the other and each consists of a body made of a strip of paper folded to form V-shaped portions 33 similar to the V-shaped portion previously described. The portions 33 however are of gradually decreasing size from the front to the rear.

Extending inwardly from one edge thereof, each member 33 (see Fig. 12) is provided with a slit 34 and a companion slit 35. In the slits 34 and 35 I arrange a spar member 36 which is of general U-shape including a base 37 and a pair of legs with one leg 38 longer than the other leg 39. The leg 38 is inserted in the slit 35 and the leg 39 is inserted in the slit 34. On its opposite edge each portion 33 includes a pair of slits 40. A spar member 41 having legs 42 and a base 43 is positioned with the legs 42 in the slits 40.

At the front and rear of the body the legs 38 and 39 are slotted as at 45 to provide a series of tongues which are overlapped with the overlapping portions glued together. This overlapping arrangement permits the spar members to be bent into the curved form shown.

The two complementary members 31 and 32 are arranged in back to back relation and a covering 44 is arranged over the two members to hold them in assembled position. After the fuselage is constructed, the wing is held thereon by snapping a rubber band 47 over the assembled parts as shown in Figs. 7 and 8.

In order to provide a tail structure for the airplane, I provide a rear member indicated at 48 in Figs. 9, 10 and 11. This member 48 is similar to the wing previously described and supports a pair of spaced rudders 49. Each of these rudders consists of a body 50 made from a blank and bent to form V-shaped portions 51. The crests of the V's on both sides of the body are provided with pairs of slits 52. The slits 52 as shown in Fig. 11 extend inwardly. A U-shaped spar member 53 is arranged on each side of the body with the legs of the spar members inserted in the slits 52 and with the bases of the spar members extending across the body and contacting only the tops of the crests. The sets of slits on the two sides of the body are in staggered relation and the spar members are consequently staggered when in place. The front and rear edges of the body 50 are provided with slits 54 and 55 and the portions of the crests of the body 50 adjacent these slits are slightly flattened so that the crests are tapered towards the edges as indicated at 56 and 57 in Fig. 11. The slits 54 and 55 allow this flattening or tapering of the crests since in assuming the position shown in Fig. 11 the flaps defined by the slits 54 and 55 are permitted to slightly overlap. A binder 57' is glued over the flaps 57' to hold them in overlapping relation.

At the lower portion of the body 50 on each side thereof I show a brace 58 which engages and is glued to the base of the adjacent spar member 53 and extends downwardly and is glued

to the crests of the adjacent V-shaped members so that a reinforcement is provided. The entire rudder is provided with a cover 59' which may be glued in place.

5 To secure the members 50 in place the spar members 53 are extended a slight distance into the adjacent tail member 48 as indicated at 59 in Fig. 10. The upper surface of the member 48 is suitably apertured to receive the members 50. Flanges 60 may be secured to the lower surface of the bodies 50 and to the upper surface of the members 48 to aid in holding the parts together.

In Fig. 13 I show a fuselage 44' which is made of a single member 31' instead of two members as shown in Fig. 12. In Fig. 13 similar parts are designated by similarly primed reference characters.

In Figs. 14 to 19 I show a modification of my invention wherein the device includes an airplane indicated generally at 70 and made from a blank 71 as disclosed. As shown, the blank is made from a single piece of paper and includes wing forming end portions 72 and intermediate fuselage portions 73.

25 The wing portions 72 are provided with slits 74 arranged in two parallel sets and with transverse score lines 75. The slits 74 are similar to slits 13, 14, 15 and 16 previously described and the score lines 75 correspond to the score lines 17 previously described. The fuselage forming portion 73 corresponds to the portions 12 previously described and the portion 73 is provided with a longitudinal score line 76.

30 The portion 73 is provided with spaced slits 77. The score line 76 is continued between the slits 77 to form a pair of tongues 79. The material is creased along the lines 80 at the roots of the tongues 79.

35 In forming the airplane from the blank shown, the material is folded along the score lines 75, 76, 78 and 80 to the position shown in Fig. 16 so that a plurality of V-grooves 81 are provided in the wing portions and a deep V-groove 82 is provided in the fuselage portion. The tongues 79 provide an aperture 83 in each side of the fuselage in the finished airplane. A flap 84 is glued to the material at each end of the apertures 83. This flap 84 bridges the apertures.

40 In the slits 74 I arrange spar members 85 which are similar to the spar members 36 and 41 previously described.

To hold the fuselage 73 in proper position I provide a reinforcing member shown in blank form in Fig. 18 and which includes a body 86 having end tongues 87 thereon. The body 86 and the end tongues 87 are provided with score lines 88 to define flaps 89 on the tongues and flaps 90 on the body. In the finished construction the body 86 spans the top of the fuselage and the tongues 90 are secured to the adjacent V-portions of the wings. These tongues are suitably notched as at 91 to receive the spar members.

45 The tongues 87 are bent within the fuselage member 73 and are glued in place as shown in the drawings.

50 After the device is completed, a suitable covering 92 is secured to the tops of the V-members to thus form a complete miniature airplane.

The portion 73 is provided with pairs of aligned tongues 93 which in the finished structure overlap and are glued together to form a reinforcement for the fuselage.

55 From the foregoing description it will be apparent that I have invented a novel miniature

airplane which can be economically manufactured and readily assembled.

Having thus described my invention, I claim:

1. In a device of the class described, an elongated body having transversely extending integral grooved portions, said grooved portions having aligned slits therein, a spar member in said slits and a cover secured over said grooved portions, and over said spar.

2. In an airplane wing, an elongated body bent to form a plurality of substantially V-shaped portions, said V-shaped portions each having a pair of spaced slits therein, each of said slits extending downwardly from one face of the associated V-shaped portion and terminating short of the opposed face of the associated V-shaped portion, an elongated spar member having portions thereon inserted in said slits, and a covering secured over the body.

3. In a device of the class described, a body part consisting of a plurality of connected substantially V-shaped portions, ribs on certain of said V-shaped portions, said ribs extending rearwardly and forwardly, said substantially V-shaped portions having slits therein, spar reinforcing members in said slits and a cover on said airfoil.

4. In a device of the class described, an elongated body part consisting of a plurality of transversely extending integral substantially V-shaped portions, certain of said V-shaped portions being extended rearwardly and forwardly, the extended portions being shaped to provide ribs, said V-shaped portions having longitudinal slits therein, U-shaped spar members in said slits and a cover secured over said V-shaped portions, and over said ribs and said spars.

5. In an airplane wing, a one piece body including a plurality of rib forming portions and integral connecting portions, said rib forming portions and said connecting portions being transversely bent to form a plurality of substantially V-shaped portions, said rib forming portions and said substantially V-shaped portions each having a pair of spaced slits therein, each of said slits extending downwardly from one face of the associated portion and terminating short of the opposed face of the associated portion, an elongated U-shaped spar member having the legs thereof inserted in said slits, the spar member having its base flush with the top of the V's and a covering secured to the rib portions and to the V-shaped portions and to the bases of the spar member.

6. In an airplane wing, an elongated body bent to form a plurality of V-shaped portions, said V-shaped portions having a pair of spaced slits extending downwardly from the top thereof and terminating short of the bottom thereof, said V-shaped portions having another pair of slits extending upwardly from the bottom thereof and terminating short of the top thereof, a pair of elongated U-shaped spar members, one of said spar members having the legs thereof inserted in said first pair of slits and the other spar member having the legs thereof inserted in the other pair of slits, the spar members telescoping one within the other, and a covering secured over the body.

7. In an airplane wing, an elongated body bent to form a plurality of V-shaped portions, said V-shaped portions having a pair of spaced slits extending downwardly from the top thereof and terminating short of the bottom thereof, said V-shaped portions having another pair of slits extending upwardly from the bottom thereof and terminating short of the top thereof, a pair of elongated U-shaped spar members, one of said

spar members having the legs thereof inserted in said first pair of slits and the other spar member having the legs thereof inserted in the other pair of slits, the spar members telescoping one within the other, the upper spar member having its base flush with the top of the V's and the lower spar member having its base flush with the bottom of the V's, rib forming members on certain of said V-shaped portions and a covering secured over the body.

8. In an airplane wing, a body including a plurality of rib forming portions and connecting portions, said rib portions being transversely bent to form a plurality of substantially V-shaped portions, said portions having a pair of spaced slits extending downwardly from the top thereof and terminating short of the bottom thereof, said portions having a second pair of slits extending upwardly from the bottom thereof and terminating short of the top thereof, a pair of elongated U-shaped spar members, one of said spar members having the legs thereof inserted in said first pair of slits and the other rail member having the legs thereof inserted in the other pair of slits, the upper spar member having its base flush with the top of the V's and the lower spar member having its base flush with the bottom of the V's and a covering secured to the tops and bottoms of the rib forming portions and to the tops and bottoms of the V-shaped portions and to the bases of the spar members.

9. In an airplane wing, a one piece body including a plurality of rib forming portions and integral connecting portions, said rib forming portions and said connecting portions being transversely bent to form a plurality of substantially V-shaped portions, said rib forming portions and said substantially V-shaped portions having a pair of spaced slits extending downwardly from the top thereof and terminating short of the bottom thereof, said rib forming portions and said substantially V-shaped portions having a second pair of slits extending upwardly from the bottom thereof and terminating short of the top thereof, a pair of elongated U-shaped spar members, one of said spar members having the legs thereof inserted in said first pair of slits and the other spar member having the legs thereof inserted in the other pair of slits, the spar members telescoping one within the other, the upper spar member having its base flush with the top of the V's and the lower spar member having its base flush with the bottom of the V's and a covering secured to the tops and bottoms of the rib forming portions and to the tops and bottoms of the V-shaped portions and to the bases of the spar members, said ribs having tongues thereon engaging said covering.

10. In an airplane fuselage, a body member including a strip bent to form a plurality of substantially V-shaped portions, said V-shaped portions having a pair of spaced slits extending downwardly from the top thereof and terminating short of the bottom thereof, said V-shaped portions having a second pair of slits extending upwardly from the bottom thereof, a pair of elongated U-shaped spar members, one of said spar members having the legs thereof inserted in said first pair of slits and the other spar member having the legs thereof inserted in the other pair of slits, and a covering secured to the tops and bottoms of the V-shaped portions and to the spar members.

11. In an airplane fuselage, a pair of body members each body member including a strip

bent to form a plurality of substantially V-shaped portions, said V-shaped portions having a pair of spaced slits extending downwardly from the top thereof and terminating short of the bottom thereof, said V-shaped portions having a second pair of slits extending upwardly from the bottom thereof, a pair of elongated U-shaped spar members, one of said spar members having the legs thereof inserted in said first pair of slits and the other spar member having the legs thereof inserted in the other pair of slits, and a covering secured to the tops of the V-shaped portions and to the bases of the spar members, the bottoms of the body members being secured together.

12. In an airplane fuselage, a pair of body members each body member including a strip bent to form a plurality of substantially V-shaped portions, said V-shaped portions having a pair of spaced slits extending downwardly from the top thereof and terminating short of the bottom thereof, said V-shaped portions having a second pair of slits extending upwardly from the bottom thereof, a pair of elongated U-shaped spar members, one of said spar members having the legs thereof inserted in said first pair of slits and the other spar member having the legs thereof inserted in the other pair of slits, the upper spar member having its base flush with the top of the V's and the lower spar member having its base flush with the bottom of the V's and a covering secured to the tops of the V-shaped portions and to the bases of the spar members, the bottoms of the body members being secured together.

13. In an airplane, a pair of body members each body member including a strip bent to form a plurality of substantially V-shaped portions, said V-shaped portions having a pair of spaced slits extending downwardly from the top thereof and terminating short of the bottom thereof, said V-shaped portions having a second pair of slits extending upwardly from the bottom thereof, a pair of elongated U-shaped spar members, one of said spar members having the legs thereof inserted in said first pair of slits and the other pair of slits, one of the spar members having one leg extending to a location adjacent to the other spar member, the upper spar member having its base flush with the top of the V's and the lower spar member having its base flush with the bottom of the V's and a covering secured to the tops of the V-shaped portions and to the bases of the spar members, the bottoms of the body members being secured together, and a wing on the fuselage.

14. In an airplane, a fuselage, a wing on the fuselage, a tail construction on the fuselage, said tail construction including an airfoil having a pair of rudders thereon, each rudder including a strip bent to form a plurality of substantially V-shaped portions, each of said V-shaped portions having spaced slits extending inwardly from the crests of the V's, an elongated spar member including portions inserted in said slits, and a covering secured to the tops and bottoms of the V-shaped portions and to the spar members.

15. In a rudder for an airplane, a strip bent to form a plurality of substantially V-shaped portions, said V-shaped portions each having a pair of spaced slits therein, each of said slits extending from one edge of the associated V-shaped portion and terminating short of the other side edge of the associated V-shaped portion, said V-shaped portions having a second pair of slits extending from the other side thereof, a pair of elongated U-shaped spar members, one of said spar members having the legs thereof inserted in said

first pair of slits and the other spar member having the legs thereof inserted in the other pair of slits, the spar members having their bases flush with the top of the V's, a covering secured to the tops and bottoms of the V-shaped portions and to the bases of the spar members, and a reinforcing member engaging the lower outer face of each rudder.

16. In an airplane, a fuselage, a wing on the fuselage, a tail construction on the fuselage, said tail construction including an airfoil having a pair of rudders thereon, each rudder including a strip bent to form a plurality of substantially V-shaped portions, said V-shaped portions having a pair of spaced slits extending from one side thereof and terminating short of the other side thereof, said V-shaped portions having a second pair of slits extending from the other side thereof, a pair of elongated U-shaped spar members, one of said spar members having the legs thereof inserted in said first pair of slits and the other spar member having the legs thereof inserted in the other pair of slits, the spar members having their bases flush with the top of the V's, a covering secured to the tops and bottoms of the V-shaped portions and to the bases of the spar members, said airfoil having spaced holes therein, one of the spar members of each pair extending beyond the rudder, the extending part of the spar members being inserted in said spaced holes and a reinforcing member engaging the lower outer face of each rudder.

17. In an airplane, a body member including a strip bent to form a relatively large intermediate substantially V-shaped portion and a plurality of smaller V-shaped portions at the ends of the intermediate portion, said end V-shaped portions having a pair of spaced slits extending downwardly from one side thereof and terminating short of the opposite side thereof, an elongated U-shaped spar member having the legs thereof inserted in said pair of slits and a covering secured to the tops and bottoms of the V-shaped portions and to the spar members, said intermediate V-shaped portion being longer than the end V-shaped portions.

18. In an airplane, a body member including a strip bent to form an intermediate relatively wide and deep substantially V-shaped fuselage forming portion and a plurality of relatively narrow and shallow substantially V-shaped wing forming portions, all of said V-shaped portions having a pair of spaced slits extending downwardly from the tops thereof and terminating short of the bottom thereof, said V-shaped portions having a second pair of slits extending upwardly from the bottom thereof, a pair of elongated U-shaped spar members, one of said spar members having the legs thereof inserted in said first pair of slits and the other spar member having the legs thereof inserted in the other pair of slits, and a covering secured to the tops and bottoms of all of the wing V-shaped portions and to the spar members.

19. In an airplane, a body including a strip bent to form an intermediate V-shaped portion and a plurality of substantially V-shaped portions at each end of the intermediate portion, each of said V-shaped portions having a pair of slits extending downwardly from the top thereof and terminating short of the bottom thereof, said V-shaped portions having a second pair of slits extending upwardly from the bottom thereof, a pair of elongated U-shaped spar members, one of said spar members having the legs thereof in-

serted in said first pair of slits and the other spar member having the legs thereof inserted in the other pair of slits, one of the spar members having one leg extending to a location adjacent to the other spar member, the upper spar member having its base flush with the top of the end V's and the lower spar members having its base flush with the bottom of the end V's, said intermediate

V-shaped portion projecting forwardly and rearwardly beyond the end V-shaped portions and a reinforcing member secured to said intermediate portion, and a covering secured to the tops and bottoms of the end V-shaped portions and to the bases of the spar members.

JOSEPH E. GRANT.
